WIRELESS APPARATUS.

1,106,875.

Specification of Letters Patent Patented Aug. 11, 1914.

Application filed April 22, 1913. Serial No. 762,772.

To all whom it may concern:

Be it known that we, PETER L. JENSEN, a subject of the King of Denmark, and EDWIN S. PRIDHAM, a citizen of the United States, both residing at Napa, in the county of Napa and State of California, have invented new and useful Improvements in Wireless Apparatus, of which the following is a specification.

10 This invention relates to wireless telegraphy, and particularly to means for reducing the disturbing effects of atmospheric electricity.

The word static is so commonly used in connection with atmospheric electricity that this kind of interference will hereinafter be termed static. The origin of static is not as well known as its manifestation. We may distinguish between two kinds of static disturbances, the one consists of electro-magnetic waves generated by a sudden discharge of electricity as in lightning. This disturbance is short and sharp in character, and produces a characteristic click in the telephone receiver. The other kind of disturbance is of a more serious nature and consists of a more or less intermittent discharge or flow of electricity in the antenna. This disturbance is often prolonged and may 30 make it impossible to read letters or entire words of an incoming message. These two forms of static can easily be duplicated in the laboratory, the first by discharge of an oscillatory nature as from a Leyden jar or 35 condenser, and the second which is a most exact imitation of the distressing static, may be shown by allowing masses of charged dust particles to strike the receiving antenna. It has been shown by conclusive experiments that these charged particles striking the antenna give rise to the disturbing currents in the receiving circuits.

The present invention relates to means for guarding the antenna from receiving charges 45 from the surrounding atmosphere and consists of surrounding the receiving antenna with conductors of certain form upon which are maintained charges of electricity.

The novelty of the invention is in the 50 maintaining of charges of electricity upon the guarding conductors and in the placing of these conductors around the receiving antenna in certain positions. A single wire

or a cage of wires without a charge on it around the antenna is of no benefit in reducing the disturbance. 55

In the invention herein described we have an antenna surrounded by a cage of wires upon which is maintained a charge of electricity and concentric with this cage is a 60 similar cage with a charge of opposite kind of electricity on it. In practice the distance between the antenna and the inner cage is greater than the distance between the two concentric cages. It is necessary that 65 the charges be maintained steady or the variation will to some degree affect the receiving antenna. The charge may be produced by a high potential battery or a static machine, or any source of steady potential. It 70 is also necessary that the frequency of the received wave be of a different order than the natural frequency of the guarding cages.

Another form of the invention consists of surrounding the receiving antenna with 75 a number of guarding wires; each alternate wire being in metallic connection, thus forming two metallic sets, substantially in the same plane, one set having a plus charge upon it, the other a negative charge. 80

Another form of the invention consists in surrounding the receiving antenna with two conducting cages, either concentric or intermeshed and insulated one from the other and connecting the one through a source of 85 positive potential to the ground and the other through a source of negative potential to the ground. 85

The invention consists of the parts and the construction and combination of parts 90 as hereinafter more fully described and claimed, having reference to the accompanying drawings, in which—

Figure 1 shows diagrammatically a plan view in cross section of the arrangement of 95 the guarding wires around the antenna. Fig. 2 shows diagrammatically the arrangement of parts in vertical cross section in connection with sources of potential and ground connections and the receiving circuit. Fig. 3 shows diagrammatically in vertical cross section a variation of the arrangement of the guarding wires around the antenna with a single source of electricity and receiving circuits. Fig. 4 shows diagrammatically in horizontal cross section 100 105

the guarding wires with opposite charges of potential on the alternate wires, and the antenna.

Referring to Fig. 1, 2 is the antenna; 3 and 4 are concentric guarding cages formed by the vertical wires v and v' , and the horizontal wires h and h' . The inner cage 3 has a charge maintained upon it and the outer cage 4 has a charge of opposite potential as indicated.

Referring to Fig. 2, 3 and 4 are the two concentric cages composed of the vertical conductors $v-v'$ and the horizontal conductors $h-h'$; 2 is the antenna connected through the primary oscillation circuit P to the ground 5. S is the secondary oscillation circuit. The inner set of conductors 3 are connected through a source of negative potential 6 to the ground 5. The outer set of conductors 4 are connected through a source of positive potential 7 to the ground 5.

Referring to Fig. 3, 3 and 4 are the guarding wires surrounding the antenna 2; the inner set of wires 3 being connected to the negative pole of a source of electricity 8 and the outer set of wires 4 is connected to the positive pole of the source of electricity 8. The antenna 2 is connected to the primary circuit P to the ground 5. S is the secondary receiving circuit.

Referring to Fig. 4 the two guarding sets of conductors are shown in horizontal view occupying substantially the same cylindrical space around the antenna 2. This arrangement may be produced by connecting each alternate wire respectively to positive and negative sources of electricity as indicated.

Having thus described our invention, what we claim and desire to secure by Letters Patent is—

1. In a wireless receiving station including a means for reducing the disturbing effects of atmospheric electricity, an antenna, a receiving circuit in connection with said antenna, means for detecting incoming electro-magnetic waves in combination with two separate sets of conductors, said sets of conductors being insulated from and substantially surrounding said antenna, and means for impressing locally charges of electricity respectively upon said sets of conductors.

2. In a wireless receiving station, including a means for reducing the disturbing effects of static, an antenna, a receiving circuit in connection with said antenna, means for detecting electro-magnetic waves striking said antenna in combination with two sets of conductors, said conductors being separate from and substantially surrounding said antenna, and means for impressing

charges of opposite sign respectively upon said sets of conductors.

3. In a wireless receiving station, including a means of improving the reception of electro-magnetic waves, an antenna, a receiving circuit in connection with said antenna, and means for detecting electro-magnetic waves in combination with two separate sets of conductors, said conductors being separate from and substantially surrounding said antenna, and means for impressing and maintaining charges of opposite character respectively between said two sets of conductors and the ground, substantially as described.

4. In a wireless receiving station, including a means for reducing the disturbing effects of static electricity, an antenna, a receiving circuit, and means for detecting electro-magnetic waves in combination with two separate concentric sets of conductors, said concentric sets of conductors being removed from said antenna and substantially surrounding the same, and means for impressing and maintaining charges of electricity of opposite sign respectively upon said concentric sets of conductors.

5. In a wireless receiving station, an antenna and a receiving circuit with means for detecting electro-magnetic waves in combination with two separate concentric sets of conductors, said concentric sets of conductors substantially surrounding said antenna, the distance between said concentric sets of conductors being less than the distance between said concentric sets of conductors and said antenna, and means for impressing charges of opposite sign respectively on said concentric sets of conductors.

6. In a wireless receiving station, including a means for reducing the disturbing effects of static electricity, an antenna, a receiving circuit and means for detecting electro-magnetic waves in combination with two separate sets of concentric conductors, said concentric sets of conductors substantially surrounding said antenna, one of said sets of concentric conductors being connected through a source of positive electricity to the ground, the other set of concentric conductors being connected through a source of negative electricity to the ground, substantially as described.

In testimony whereof we have hereunto set our hands in the presence of two subscribing witnesses.

PETER L. JENSEN.
EDWIN S. PRIDHAM.
